STANDARDIZING CENTRIFUGALLY
SEPARABLE PRODUCT

Donald F. Ayres, Poughkeepsie, N. Y., assignor to
The De Laval Separator Company, New York,
N. Y., a corporation of New Jersey

Application August 26, 1947, Serial No. 770,586

17 Claims. (Cl. 233—19)

1

This invention relates to centrifugal separation and has for its object to provide an improved method and apparatus for standardizing the concentration of a constituent of a centrifugally separable product by automatically regulating one of the separating conditions.

In the preferred practice of the invention, a part of the centrifugally separated constituent is re-centrifuged in a pilot separator, thereby separating it into an effluent and a more highly concentrated constituent. Light from a source of predetermined intensity is directed through the contents of the pilot centrifuge chamber upon a light sensitive element, preferably in a direction generally parallel to the chamber axis of rotation and in the vicinity of the "neutral zone" in the chamber. In this way, small changes in the concentration of the constituent fed to the pilot centrifuge will cause greater changes in the quantity of light transmitted through the contents of the pilot chamber to the light-sensitive element, due to the high concentration of the constituent in the region where the light is transmitted.

The pilot centrifuge is preferably provided with a separating bowl having top and bottom walls of transparent material, the bowl also having a central inlet for the feed and separate outlets at different radii for the separated effluent and concentrated constituent, respectively. The light source and the light-sensitive or photo-sensitive element may then be arranged in stationary positions outside the bowl, so that the light is directed upon one of the transparent walls and is emitted from the other wall in passing to the light-sensitive element.

The signals or indications from the photo-sensitive element may be used to control the rate of feed to a primary centrifuge of the "open" type having free discharge for both separated constituents. However, when the primary centrifuge is of the "closed" type having the discharge of at least one of the constituents opposed by a variable resistance, the photo-sensitive element should be arranged to control the variable resistance in the constituent outlet.

For illustrative purposes, the invention will be described in connection with standardizing the butter fat content of cream, although it is to be understood that the invention may be used as well for treating other products having a centrifugally separable constituent whose concentration is to be standardized.

In dairy practice, the cream is usually standardized to a fat content of approximately a predetermined proportion, depending upon the use

2

for which the cream is intended. This standardizing operation is important because the butter fat is by far the most valuable constituent of the product. Heretofore, it has been common practice to concentrate the cream as closely as possible to the desired fat content by centrifugally separating skim milk from the cream, the centrifugal separator being so adjusted at the outlets for the separated skim milk and cream constituents that the discharged cream will have approximately the desired fat content. It is well known, however, that cream separators of the centrifugal type are sensitive to variations in feed rate, temperature of the feed, and back-pressure at either of the separated constituent outlets. These variations in external conditions often occur in the dairy, and accordingly it is necessary to readjust the centrifugal separator frequently to compensate for them. Such readjustments are objectionable not only because of the demands upon the operator but also because it is not always possible, due to the human element, to obtain in the discharged cream a fat content within the desired limits. Consequently, after the centrifugal separating operation, it is often necessary to effect an additional adjustment of the fat content of the cream, as by adding heavier cream or skim-milk, to avoid an insufficiency or excess of butter fat.

A more specific object of the present invention, therefore, resides in the provision of an improved process by which the centrifugally separated cream is standardized automatically and accurately within the desired limits, with respect to the fat concentration, and a novel apparatus by which the process can be practiced expeditiously.

According to a preferred form of the invention as applied to the standardizing of cream, the milk or partly concentrated cream is fed to a primary centrifuge of the "closed" type having the discharge of the cream opposed by a variable resistance, such as a valve, and wherein skim milk is removed and discharged separately from the cream. Part of the discharged cream is then fed to a pilot separator wherein variations of the light-transmitting ability of the cream are determined. This determination is effected automatically by passing light from a source of predetermined intensity through the cream and upon a light-sensitive element, such as a photo-cell. The light-sensitive element, in turn, is connected to the valve or other variable resistance and operates to vary this resistance in accordance with changes in the amount of light transmitted by

the discharged cream to the photo-sensitive element. That is, when the discharged cream passing to the light source has a fat content above the desired proportion, the additional fat globules will reduce the amount of light transmitted to the light-sensitive element, which will cause operation of the variable resistance to decrease the resistance to discharge of cream from the centrifuge, thereby reducing the fat content of the discharged cream. When this fat content becomes too low, a reverse operation is effected. Thus, the fat content of the discharged cream is automatically maintained substantially constant, irrespective of variations in the external conditions affecting the centrifuge.

When it is desired to standardize milk by removing excess cream, the feed to the pilot centrifuge is derived from the standardized milk discharged from the primary centrifuge, rather than from the discharged cream.

For a better understanding of the invention reference may be had to the accompanying drawings, in which

Fig. 1 is a schematic view of a preferred form of the new apparatus, showing in vertical section the pilot centrifuge and light-responsive device for determining variations in the light transmitting ability of the discharged cream;

Fig. 2 is an enlarged vertical sectional view of part of the apparatus illustrated in Fig. 1, showing the valve arrangement for varying the resistance to discharge of the separated cream from the primary centrifuge, and

Fig. 3 is a schematic view of the electrical circuits for adjusting the regulating valve under control of the photo-sensitive element.

The apparatus as illustrated comprises a centrifugal separator 10 which is preferably of the "air-tight" type wherein the centrifugal bowl has inlet and outlet connections closed to the atmosphere. The milk or partly concentrated cream is fed to the centrifuge through a supply pipe 11, and the skim milk and the standardized cream are discharged separately through outlets 12 and 13, respectively. The cream discharge is provided with a regulating device, shown generally at 14, by which the resistance to discharge of the separated cream from the centrifuge bowl may be varied. The regulating device 14 may be of the type disclosed in Patent No. 2,145,544 of C. H. Hapgood, dated January 31, 1939. As shown particularly in Fig. 2, the device 14 comprises a vertical pipe 15 located on top of the cover 10 for the centrifuge frame, above the skim milk outlet 12. The pipe 15 is secured to the frame cover by a threaded ring 16 and communicates through a central passage 17 in the cover, and through the usual tightening device or seal (not shown), with the cream outlet from the rotating bowl. Interposed between the pipe 15 and the passage 17 is a valve seat 18 having a centrally depressed portion 18^a provided with valve openings 18^b. A valve member in the form of a disc 19 normally engages the top of the seat 18 and has a central opening through which the reduced end 20 of a stem 21 extends, the lower part of the extension 20 being guided in a central opening in the depressed part of the valve seat. Separated cream from the centrifugal bowl is adapted to flow upwardly through passage 17 and openings 18^b and lift the valve disc 19, due to the discharge pressure of the cream, whereby the latter flows outwardly around the periphery of disc 19 and up through the pipe 15, finally passing through the outlet 13.

4

A flexible diaphragm or membrane 23 is disposed at the upper end of pipe 15 where it is clamped in position by a superimposed casing 24, the parts 24 and 15 being held together by a threaded ring 25. The stem 21 fits closely in a central opening in diaphragm 23 and at its upper end engages a plunger 21^a slidably in the bottom wall 24^b of casing 24. The plunger 21^a is urged downwardly by a compression spring 26 coiled around the lower end of a threaded shaft 27, the upper end of the spring engaging a shoulder on the shaft. Thus, the spring acts to depress the plunger, the stem 21 and diaphragm 23, so that the shoulder near the lower end of the stem holds the valve 19 against its seat with a yielding resistance to the discharge of cream. The shaft 27 extends upwardly through a central opening in a horizontal wall 24^c in the casing and through an upwardly extending hollow boss 24^c on the horizontal wall. Within the boss 24^c, the shaft 27 is provided with a vertical groove 27^a into which a pin 28 projects from the boss.

The shaft 27 is adjustable vertically in boss 24^c by means of a worm wheel 30 having internal threads mating with the external threads at the upper portion of the shaft. The worm wheel 30 is held against the top of boss 24^c by a collar 31 surrounding the shaft and interposed between the worm wheel and the closed upper end of casing 24. An extension 27^b of the shaft projects upwardly through a central opening in the top of casing 24, for a purpose to be described presently. The worm wheel 30 meshes with a worm 32 mounted on a horizontal shaft 33 extending through the casing wall from a reversible electric motor 34 adapted to be energized from the line conductors 35, 35^a.

It will be understood that when motor 34 rotates in one direction, the worm wheel 30 will be driven so as to elevate the shaft 27, which is held against rotation by the pin 28 in groove 27^a. As a result, the force of spring 26 against plunger 21^a and valve disc 19 will be reduced, thereby reducing the resistance to discharge of the separated cream constituent from the centrifugal bowl. This, in turn, will cause a larger amount of skim milk to discharge with the cream through outlet 13, so as to reduce the proportion of butter fat in the cream. Conversely, when motor 34 is rotated in the opposite direction, the threaded shaft 27 will be lowered to impose additional compression in spring 26 and thus increase the resistance to discharge through cream valve 19, whereby the proportion of butter fat in the cream from outlet 13 will be increased.

This discharged cream from outlet 13 passes through a cream line 36 from which a branch bleeder line 37 extends to a pilot centrifuge 38. As shown in Fig. 1, the centrifuge 38 comprises a centrifugal bowl 39 made of transparent material, such as a plastic. The bowl 39, which may be formed by molding the plastic, is provided with a separating chamber 40 and an axial spindle 41 by which the bowl is supported and rotated in a suitable frame (not shown). A neck 42 projects upwardly from the bowl 39 and has a central inlet passage 43 for receiving the cream from the bleeder line 37, the cream flowing downwardly through passage 43 and outwardly through passages 44 into the separating chamber. The cream entering chamber 40 is centrifugally separated into an outer annulus of skim milk and an inner annulus of cream. Cream from the inlet annulus is constantly discharged from the separating chamber through an outlet passage

45 leading upwardly through neck 42 to a stationary collecting cover 46 having a discharge spout 46^a. The separated skim milk is discharged from the outer part of chamber 40 through a passage 47 extending upwardly within the neck 42 to cover 46, from which the skim milk is discharged with the cream through spout 46^a. The cream discharge may be adjusted by a regulating screw 48 near the discharge end of passage 47.

The pilot bowl 38 is of the "ratio" type designed to allow "run ahead" of the separated constituents in their discharge from the separating chamber.

Adjacent the bowl 39 is an opaque casing 50 having a horizontal partition 50^a dividing the casing into two compartments. In the upper compartment is a light source 51, which may be an incandescent lamp, from which light passes through a small opening or slit 51^a in the casing 50. The light emitted from opening 51^a is conducted by a light-transmitting member 52, which may be made of Lucite, or the like, to the wall forming the top of separating chamber 40. A similar light-transmitting member 53 is located below the bowl 39 in position to receive light transmitted through the separating chamber from the member 52. The light received by member 53 passes through a small opening or slit 53^a in the lower part of casing 50 and impinges upon a photo-sensitive element 54, such as a photo-cell, arranged in the lower compartment of the casing. The photo-sensitive element 54 is connected to an electrical control system, indicated generally at 55 in Fig. 1, by wires 56, the system 55 in turn being connected to the reversible electric motor 34 to effect adjustment of the regulating device 14.

The details of the electrical control system 55 are illustrated in Fig. 3. As there shown, the wires 56 connect the photo-cell in circuit with the actuating coil 57^a of a micro-ammeter 57 having the usual pointer 58. At opposite sides of the pointer 58 are stationary permanent magnets 59 and 59^a which are so arranged that when the pointer swings in either direction from its central position, due to a variation in the current through wires 56 from the photo-cell, the adjacent magnet will attract armature 58^a on the pointer and hold the latter against the magnet. Assume that the pointer 58 swings to the left due to a decrease in the fat content in separating chamber 40 and a consequent increase in the amount of light received by photo-cell 54 (thus increasing the current flowing through wires 56 and the ammeter). The pointer will then be attracted to and held against magnet 59 so as to engage contact 60. As a result, a circuit will be established from one side 35 of the current source through wire 61, terminal 62, arm 58, contact 60, wire 63, relay 66 and wire 67 to the other side 35^a of the current source, so that the relay 66 is connected across the line 35-35^a. As a result, the relay 66 will operate switch 68 so as to engage the switch arms 69 and 70 with contacts 71 and 72, respectively. A circuit will then be established from conductor 35^a through the lower field winding 34^a of the motor, wire 73, contact 72, switch arm 70, wire 74, the rotor 34^b of the motor, wire 75, switch arm 70^a, contact 76^a, wire 65, switch 64 and the upper field winding 34^b to conductor 35, thus causing the motor to drive shaft 33 in the direction for lowering shaft 27 and increasing the proportion of

butter fat in the cream discharged through outlet 13.

Simultaneously with the energizing of motor 34, another circuit is established from conductor 35 through wires 61 and 77, contact 71, switch arm 69, wires 78 and 80, slow-acting relay 81, and wires 82, 83 and 67 to the other conductor 35^a. After a predetermined time interval (which may be in the order of one-half of a second) following the energizing of relay 81, the latter closes switch 84-85 so as to energize the reset coil 86 associated with ammeter 57, the reset coil then returning the pointer 58 to its central position against the action of magnet 59. It will be understood that when the pointer 58 is returned to its central position, the contact 60 is disengaged so as to de-energize relay 66, whereupon switch 68 returns to its initial position so as to de-energize the motor 34 and the slow-acting relay 81.

When the fat content of the cream discharged through outlet 13 exceeds the predetermined proportion, the concentration of fat globules in pilot chamber 40 will quickly increase, this condition being manifested by a tendency for the "cream" line in chamber 40 to move outwardly toward the separated skim milk constituent. As a result, the amount of light transmitted through chamber 40 from the light source 51 to the photo-cell 54 will be correspondingly decreased, thereby decreasing the current flowing through wires 56 and ammeter 57. This will cause pointer 58 to swing to the right until it is attracted by and held against the other magnet 59^a. Thereupon, a circuit will be established from conductor 35 through wire 61, arm 58, contact 60^a, wire 63^a, relay 66^a, and wires 83 and 67 to the other conductor 35^a. Relay 66^a will then actuate switch 68^a to cause the switch arms 69^a and 70^a to engage contacts 71^a and 72^a, respectively. A circuit will then be established from conductor 35^a through the lower field winding 34^a, wires 73 and 88, contact 72^a, arm 70^a, wire 75, rotor 34^b, wire 74, arm 70, contact 76, wire 89, switch 64^a and the upper field winding 34^b to the other conductor 35, thus causing the motor to operate in the reverse direction so as to raise shaft 27 and decrease the proportion of butter fat in the cream discharged through outlet 13. At the same time, another circuit is established from conductor 35 through wires 61 and 77^a, contact 71^a, contact arm 69^a, wire 80, slow-acting relay 81, and wires 82, 83 and 67 to the other conductor 35^a. After a predetermined time interval, the relay 81 will then close switch 84, 85 so as to energize the reset coil 86 and return pointer 58 to its central position, as previously described, whereupon relay 66^a will be de-energized so as to open the circuits through motor 34 and relay 81. Due to the permanent magnets 59, 59^a and the reset coil 86 with its slow-acting relay 81, the motor 34 will be energized for a predetermined time interval whenever pointer 58 is displaced from its central position in response to an excess or insufficiency of butter fat in pilot chamber 40. If the control system should have a tendency to "hunt," the effective delay produced by slow-acting relay 81 may be enhanced by connecting a condenser 87 in parallel with the reset coil 86. In order to prevent extreme movements of the threaded shaft 27, with consequent damage to the cream valve regulating mechanism, the extension 27^b of the shaft is provided with a cam 90 adapted to actuate plungers 91 and 92 associated with switches 64 and 64^a, respectively.

When the shaft 27 reaches its desired upper limit, the cam 80 operates plunger 82 to open switch 64 and de-energize the motor 34, and when the shaft 27 reaches its desired lower limit, the cam 80 operates plunger 81 to open switch 64 and de-energize the motor.

It will be apparent from the foregoing that the method and apparatus of the present invention provide a completely automatic control of the fat content of cream discharged from the primary centrifuge through line 36, so that the discharged cream will be standardized to a predetermined fat content within close limits, regardless of variations in the fat content of the feed to the primary separator through supply line 11, or other external conditions. By accurately positioning the opening 51^a for the light from lamp 51, and by selecting a suitable configuration for the light-transmitting member 52, the light may be directed through the pilot separating chamber 40 in a closely confined path located approximately at the "cream line" dividing the separated cream and skim milk constituents within chamber 40. Thus, when the "cream line" moves outwardly or inwardly in chamber 40 due to an increase or decrease, respectively, in the fat content in the lines 36 and 37, the relatively opaque cream constituent will immediately intercept some of the light rays or allow additional light rays to be transmitted, depending upon the direction of movement of the "cream line." Instead of limiting the light transmission through chamber 40 to a closely confined path, the opening 51^a and member 52 may be arranged to direct the light through the chamber in a relatively wide path in the vicinity of the "cream line," whereby the light transmitted to photo-cell 54 will represent an average of the light transmitting ability (and therefore the fat content) of a substantial portion of the contents of chamber 40. The latter arrangement, that is, scanning a relatively wide path in the vicinity of the cream line, is preferred since it provides a continuously variable control by means of the electrical circuit through the photo-cell and micro-ammeter. The closely confined or "pin-point" light circuit, on the other hand, provides a more "on and off" type of control and will operate best with a polarized relay in place of the micro-ammeter. In either case, the pilot centrifuge 38, by continuously concentrating the butter fat in the standardized cream sample, makes the photo-cell 54 more sensitive to changes in the fat content of the standardized cream.

In practice, the regulating screw 48 of the pilot separator is adjusted for the approximate fat content desired. This adjustment will cause the "cream line" in the pilot centrifuge to be positioned at the approximate center of the scanning area in the bowl at a certain throughput rate of a certain fat content feed to the bowl. Thereafter, the only necessary adjustment by the operator is the adjustment of the current flow in the circuit of the photo-cell and micro-ammeter, and this may be effected by a variable resistance (not shown) in the circuit. By means of the latter adjustment, when the standardized product has the desired fat content, sufficient current will flow through the circuit to position the micro-ammeter pointer at the mid-point of its scale. For example, if the ammeter scale should read from 0 to 10 microamperes, the current flow should be adjusted to 5 microamperes at the desired fat content. In the following

claims, the term "neutral," as applied to the position of the pointer or movable member of the micro-ammeter or other electromagnetic device, is intended to denote its position at the center or mid-point of its range of movement.

The invention may be used for standardizing not only whole milk and cream but also various milk products, such as cheese mixes, butter, ice cream, condensed milk and evaporated milk. In fact, the invention may be used for standardizing any mixture with respect to the concentration of a centrifugally separable ingredient thereof, where the light-transmitting ability of the mixture varies in accordance with such concentration.

When the invention is to be used for standardizing whole milk, the bleed line 37 to the pilot centrifuge will be connected to the standardized milk discharge line from outlet 12, instead of the cream discharge line 36 carrying the surplus cream. In other words, the bleed line is arranged to convey a sample of whichever discharge (from the primary centrifuge) is to be standardized. For some purposes the regulating device 14, instead of controlling the lighter discharge, may be arranged to control the heavier discharge through outlet 12, or to control the feed through pipe 11 when the primary centrifugal bowl is of the "open" type in which the rate of feed influences the concentration of the cream or other separated constituent. In separating oil from water, for example, with a "balanced column" type of primary centrifugal bowl, part of the unwanted constituent (water discharge) may be piped to the pilot centrifuge; and the regulating device 14 may be arranged to control the rate of feed through pipe 11, or to control the discharge pressure on the wanted constituent (oil) when the primary bowl is of the "hermetic" type.

The pilot centrifuge, of course, may be of any desired construction in which, for a given rate of feed to the pilot bowl, the inner annulus forming the lighter separated constituent in the bowl will expand outwardly as the proportion of the lighter constituent in the feed increases, and will contract inwardly as this proportion decreases, so that the photo-sensitive element will respond to either an increase or a decrease in the concentration of the butter fat or other centrifugally separable constituent in the feed. While I have shown the light source and the photo-cell arranged outside the pilot bowl and stationary, they may be disposed in the bowl chamber so as to rotate therewith (the electrical connections being made through brushes, or the like, on the bowl shaft), in which case it is unnecessary to provide transparent walls for the bowl. Also, instead of directing the light through the pilot chamber parallel to the bowl axis and between the radially displaced outlets for the respective separated constituents, the light source and photo-cell may be arranged so that the light is directed radially through the annulus forming one of the separated constituents in the pilot chamber, whereby radial expansion or contraction of this annulus in response to changes in the concentration of the cream or other feed to the pilot bowl will vary the amount of light transmitted to the photo-cell. For illustrative purposes, the pilot centrifuge is shown in Fig. 1 as being larger than the primary centrifuge, although it will be understood that the pilot centrifuge will normally be considerably smaller than the primary centrifuge.

I claim:

1. Apparatus for automatically maintaining

substantially constant the concentration of the separated constituent discharged from one of the outlets of a centrifugal separator, which comprises a device connected to the separator for regulating the concentration of said last constituent, a pilot centrifuge having a centrifugal separating chamber and a light source for supplying light rays to the chamber, a duct leading to the pilot centrifuge from one of said outlets for conveying at least part of the discharge therefrom to said chamber, a photo-cell coaxing with the light source to receive light rays passing through the chamber from said source, the intensity of the light received by said cell from the source being dependent upon the light-transmitting ability of the content of the chamber where the light rays pass, and an operative connection between said cell and the regulating device for actuating the device in accordance with the intensity of the light received by the photo-cell, whereby said device counteracts changes in said concentration.

2. Apparatus as defined in claim 1, in which the regulating device includes a valve in one of said outlets, and a regulating mechanism connected to the valve for varying the position thereof to change the discharge pressure at said last outlet, said operative connection being connected to the valve regulating mechanism.

3. Apparatus as defined in claim 1, in which the regulating device includes a valve in the outlet for the constituent whose concentration is to be maintained substantially constant, and a regulating mechanism connected to the valve for varying the position thereof to change the discharge pressure at said last outlet, said operative connection being connected to the valve regulating mechanism.

4. Apparatus as defined in claim 1, in which said duct leads from the outlet for the constituent whose concentration is to be maintained substantially constant.

5. Apparatus as defined in claim 1, in which said duct leads from the outlet for the constituent whose concentration is to be maintained substantially constant, and in which the regulating device includes a valve in one of the outlets for varying the resistance to discharge therethrough.

6. Apparatus as defined in claim 1, in which the separating chamber of the pilot centrifuge has walls of light-transmitting material, the light source and the photo-cell being located outside said chamber.

7. Apparatus as defined in claim 1, in which the separating chamber of the pilot centrifuge has top and bottom walls of light-transmitting material, the light source and the photo-cell being located outside said chamber and arranged, respectively, to deliver light to one of said walls and to receive light from the other wall.

8. Apparatus as defined in claim 1, in which the separating chamber of the pilot centrifuge has top and bottom walls of light-transmitting material, the light source and the photo-cell being located outside said chamber, a light-transmitting member extending from the light source to a point adjacent the outer face of one of said walls, and a light transmitting member extending to the photo-cell from a point adjacent the outer face of the other wall.

9. Apparatus as defined in claim 1, in which said chamber has outlets for separated heavier and lighter constituents, respectively.

10. Apparatus as defined in claim 1, in which

said operative connection includes a reversible electric motor connected to the regulating device, an electromagnetic device connected to the photo-cell and having a member movable to one side of a neutral position upon an increase in said light intensity above a predetermined normal intensity, and to the opposite side upon a decrease in said intensity below the predetermined normal, a source of electrical energy, and means under control of said movable member for connecting the source to said motor to drive the same in one direction upon movement of the member to said one side, and for connecting the source to the motor to drive the same in the opposite direction upon movement of the member to said opposite side.

11. Apparatus as defined in claim 1, comprising also means for limiting the movement of the regulating device through said operative connection.

12. Apparatus as defined in claim 1, in which said operative connection includes a reversible electric motor connected to the regulating device, an electromagnetic device connected to the photo-cell and having a member movable to one side of a neutral position upon an increase in said light intensity above a predetermined normal intensity, and to the opposite side upon a decrease in said intensity below the predetermined normal, a source of electrical energy, means under control of said movable member for connecting the source to said motor to drive the same in one direction upon movement of the member to said one side, and for connecting the source to the motor to drive the same in the opposite direction upon movement of the member to said opposite side, and means coaxing with said movable member for retaining the same on one side of its neutral position for a predetermined time interval after initial movement of the member to said side.

13. Apparatus as defined in claim 1, in which said operative connection includes a reversible electric motor connected to the regulating device, an electromagnetic device connected to the photo-cell and having a member movable to one side of a neutral position upon an increase in said light intensity above a predetermined normal intensity, and to the opposite side upon a decrease in said intensity below the predetermined normal, a source of electrical energy, means under control of said movable member for connecting the source to said motor to drive the same in one direction upon movement of the member to said one side, and for connecting the source to the motor to drive the same in the opposite direction upon movement of the member to said opposite side, and limit switches included in said connecting means and operable by the regulating device to disconnect the motor from the source.

14. Apparatus for automatically maintaining substantially constant the concentration of one of the constituents separated in and discharged from a centrifugal separator, which comprises a device connected to the separator for regulating the concentration of said one constituent, a pilot centrifuge having a centrifugal separating chamber, a duct leading to the pilot centrifuge from one of said outlets for conveying at least part of the discharge therefrom to the pilot chamber, said chamber being adapted to separate said part centrifugally into concentric annuli having relatively high and low concentrations, respectively, of said one constituent, the chamber having separate

outlets for discharge from the respective annuli, means coacting with the pilot centrifuge and responsive to variations in the relative volumes of said annuli in the chamber, and an operative connection between said means and the regulating device for actuating the device to counteract said variations.

15. In combination with a centrifugal separator having two discharge outlets, one for each of the separated constituents, an apparatus for controlling the concentration of one of said constituents, which comprises a device for throttling the discharge of the concentrated constituent, a pilot centrifugal separator, a feed line from said first separator to the pilot separator through which a portion of said discharged concentrated constituent is fed, the pilot separator being operable to separate said portion into two components in concentric annuli and having outlets for the continuous discharge of said components, and means, responsive to changes of the zone of division between said annuli, for operating the throttling device to control the amount of said throttling.

16. A method for standardizing the concentration of one of the constituents separated in and discharged from a locus of centrifugal force, which comprises opposing the discharge of one of the constituents with a variable resistance, continuously feeding from said locus to another locus of centrifugal force at least part of the discharged constituent whose concentration is to be standardized, centrifuging said part in the second locus to separate said part into constituents having relatively high and low concentrations, respectively, continuously discharging said last

separated constituents from the second locus, passing light at constant intensity through the second locus in a direction generally parallel to the rotation axis thereof and in a region where changes in the relative amounts of said last separated constituents will vary the amount of light transmitted through the second locus, and varying said resistance in accordance with variations in the amount of light transmitted through the second locus.

10 second locus.

17. A method as defined in claim 16, in which said variable resistance opposes the discharge of the constituent whose concentration is to be standardized.
